ROTARY PUMP

Anthony C. Mamo, Des Plaines, and Boleslaw Pietraszewski, Chicago, Ill., assignors to Borg-Warner Corporation, Chicago, Ill., a corporation of Illinois

Filed Mar. 27, 1961, Ser. No. 98,483
6 Claims. (Cl. 103—136)

This invention relates to a positive-displacement hydraulic pump and more particularly to a pump of this type comprising a cylindrical casing having a cylindrical rotor mounted eccentrically therein which is provided with but one vane having a sealing roller at the end thereof.

It is an important object of this invention to provide an improved pump of this type wherein the rotor is provided with an intake cavity on one side thereof and an outlet cavity on the other side thereof.

It is another object of this invention to provide a rotor having one vane with a roller at the end thereof in sealing engagement with the inner periphery of the casing and another roller in the casing extending through the inner periphery thereof in sealing engagement with the rotor.

It is also an object of this invention to provide a pump of this type which is economical to manufacture.

This invention consists of the novel constructions, arrangements and devices to be hereinafter described and claimed for carrying out the above stated objects and such other objects as will appear from the following description of a preferred form of the invention, illustrated with reference to the accompanying drawings, wherein:

FIG. 1 is a cross sectional view taken on line 1—1 of FIG. 2 of a pump constructed according to this invention;

FIG. 2 is a view taken on line 2—2 in the direction as shown in FIG. 1; and

FIG. 3 is a view taken on line 3—3 in the direction as shown in FIG. 1.

Like characters of reference designate like parts in the several views.

Referring now to FIG. 1, a cylindrical casing 10 is shown, which comprises a main portion 11 and a cover plate 12. The main portion 11 has a peripheral wall 13. Bolts 14 are provided for attaching the cover plate 12 to the main portion 11 thereby providing a cylindrical cavity 15 within the cylindrical casing 10. A cylindrical rotor 16 is positioned within the cylindrical cavity 15 and is of a width to provide adequate tolerance for rotative movement between side walls 17 and 18 of the cavity 15 and yet of adequate width to minimize fluid loss. The cylindrical rotor 16 has a medial wall 19 thereby providing a suction inlet cavity 20 on one side thereof and a pressure outlet cavity 21 on the other side thereof which are of appreciable volumetric capacity. The wall 19 has a thickened wall portion 22 of a width equal to that of the rotor 16 and extends outwardly to the perimeter 23 of the rotor 16 and inwardly beyond the center thereof. The thickened wall portion 22 is provided with a rectangular recess 24 extending radially from a point short of the center of the rotor 16 and through its outer perimeter 23. A vane 25 is slideably mounted within the recess 23 and carries a roller 26 of a length equal to the width of the rotor 16, within a cylindrical bore 27 which passes through the outer end of the arm 25 and at a right angle with respect to the rotor 16. The location of the bore 27 is such that it cuts through an outer end face 28 of the arm 25 thereby permitting the roller 26 to protrude therethrough. A spring 29 is biased between the arm 25 and an inner wall 30 of the recess 24.

The rotor 16 is provided with a bore 31 extending concentrically therethrough in coaxial alignment with a

2

pair of bores 32 and 33 extending through the casing 10. The bores 32 and 33 are eccentrically positioned with respect to the cylindrical cavity 15. A shaft 34 is keyed within the bore 31 by a key 35 and journaled within the pair of bores 31 and 32 whereby the rotor 16 is mounted eccentrically within the cavity 15.

The peripheral wall 13 is provided with a bore 36 extending at right angles through a face 37 of the peripheral wall 13 and of a depth less than the width of the cylindrical cavity 15 and positioned medially with respect thereto. The location of the bore 36 is such that it cuts through an inner peripheral face 38 of the peripheral wall 13 thereby providing an opening 39 in communication with the cylindrical cavity 15 and a pair of lands 40 and 41 on opposite sides of the opening 39 whereby the roller 26 may ride on the lands 40 and 41 as it moves across the opening 39. A space 42 is provided in the bore 36 opposite the opening 39 thereby providing an area for the insertion of a flat spring 43 for urging a sealing roller 44, carried in the bore 36, into sealing engagement with the outer periphery 45 of the rotor 16.

The casing 10 is also provided with a small bore 46 extending through the inner peripheral face 38 into communication with the bore 36 thereby providing admission 25 of hydraulic fluid into the bore 36 which provides pressure as an additional means for urging the sealing roller 44 inwardly.

The side wall 17 has a suction intake port 47 therethrough in communication with the suction inlet cavity 30 and the side wall 18 has a pressure outlet port 48 in communication with the pressure outlet cavity 21. The suction inlet cavity 20 is provided with an outlet port 49 in communication with a fluid working space 50 which comprises the space between the outer periphery 45 of the rotor 16 and the inner peripheral face 38 of the peripheral wall 13. The pressure outlet cavity 21 is provided with an inlet port 51 which is also in communication with the fluid working space 50.

In operation, when the system is filled with fluid and the vane 25 is retracted at the bottom or radial innermost position of its stroke, the suction intake port 47 and the pressure outlet port 48 are momentarily closed by the thickened wall portion 22 which has a greater axial width than the diameters of ports 47 and 48. As the vane 25 moves slightly beyond this point in a clockwise direction, both ports 47 and 48 begin to open and the fluid in the fluid working space 50 is driven ahead of the vane through the inlet port 51 into the pressure outlet cavity 21 and thence through the pressure outlet port 48 as indicated by the arrows 52 in FIG. 2 and at the same time hydraulic fluid is being sucked into the fluid working space 50 by way of suction intake port 47, suction inlet cavity 20 and outlet port 49 as indicated by arrows 53 as shown in FIG. 3.

It will be apparent that when the pump is in operation, the suction inlet cavity 20 and the pressure outlet cavity 21 are always filled with fluid, as also is the fluid working space 50. Fluid loss is kept to a minimum by providing close tolerances between the sides of the cylindrical rotor 16 including the sides of the vane 25 and the side walls 17 and 18 of the cavity 15. Effective sealing against fluid loss between the end of the vane 25 and the inner peripheral face 38 of the peripheral wall 13 is provided by the roller 26 biased thereagainst by the spring 29, and the sealing roller 44 being biased against the outer periphery 45 of the rotor 16, is effective in sealing against fluid loss between the outer periphery 45 of the rotor 16 and the inner peripheral face 38 of the peripheral wall 13.

It is apparent from the above description of the operation of the pump, according to this invention, and the drawings that when the vane 25 is at the bottom of its stroke, the fluid working space 50 is completely filled and

as the vane 25 is moved in a clockwise direction by the rotation of the rotor 16, all the fluid from the fluid working space 50 is removed when the vane 25 again arrives at the bottom of its stroke and that in the meantime the fluid working space 50 has again been filled whereby with each revolution a full charge of fluid is delivered by the pump.

We wish it to be understood that our invention is not to be limited to the specific constructions and arrangements shown and described except only insofar as the appended claims may be so limited, as it will be apparent to those skilled in the art that changes may be made without departing from the principles of the invention.

We claim:

1. A rotary pump comprising a casing having a peripheral wall and first and second side walls thereby providing a cylindrical cavity therein, a cylindrical rotor having first and second sides mounted eccentrically within said cylindrical cavity by means of a shaft fixed concentrically in said rotor and journaled in the said side walls of the said casing thereby providing a fluid working space between the outer periphery of the said rotor and the inner periphery of said peripheral wall, said rotor having a first cavity in said first side thereof and a second cavity in said second side thereof, an intake port in said first side wall in communication with said first cavity, an outlet port in said second side wall in communication with said second cavity, a first port in said first cavity in communication with said fluid working space, a second port in said second cavity in communication with said fluid working space, said rotor having a radial recess, a vane defining means slideably mounted in said rotor recess, and a spring interposed between said rotor and said vane, urging said vane radially outwardly.

2. A rotary pump according to claim 1 wherein the said vane carries a sealing roller in a bore that cuts through the end of the said vane at its most radially outward end whereby the said roller contacts the said inner periphery of said peripheral wall in sealing engagement.

3. A rotary pump according to claim 1 wherein said rotor is provided with a medial wall between said first and second cavities said medial wall having a thickened portion extending from the said outer periphery of said rotor and radially inwardly beyond the center thereof and of a width equal to the width of said rotor, said thickened portion having a recess, the said vane being slideably mounted therein, said vane having a width equal to the width of said rotor and the said thickened portion being of a width greater than the diameters of the said inlet and outlet ports.

4. A rotary pump comprising a casing having a peripheral wall and first and second side walls thereby providing a cylindrical cavity therein, said peripheral wall having a bore laterally therethrough which cuts through the inner periphery of said peripheral wall thereby providing an opening in communication with said cylindrical cavity, a sealing roller in said bore, a spring interposed between said sealing roller and said peripheral wall, a cylindrical rotor mounted eccentrically within said cylindrical cavity by means of a shaft fixed concentrically in said rotor and journaled in the said side walls of the said casing thereby providing a fluid working space between the outer periphery of the said rotor and the inner periphery of said peripheral wall said rotor having a first cavity in said first side thereof and a second cavity in said second side thereof, an intake port in said first side wall in communication with said first cavity, an outlet port in said second side wall in communication with said second cavity, a first port in said first cavity in communication with said fluid working space, a second port in said second cavity in communication with said fluid working space, said rotor having a radial recess, a vane slideably mounted in said rotor recess, and a spring interposed between said vane and said rotor urging said vane outwardly.

5. A rotary pump according to claim 4 wherein the said bore is of a depth less than the width of the said cylindrical cavity and positioned medially with respect thereto the said cylindrical cavity thereby providing a pair of lands at each end of the said opening.

6. A rotary pump according to claim 4 including a second bore adjacent the said bore and extending through the said inner periphery of said peripheral wall in communication with said bore.
